UNITED STATES PATENT OFFICE.

ECTOR F. MARCEAU, OF EAST HARTFORD, CONNECTICUT.

INK-DISTRIBUTER FOR PRINTING-PRESSES.

1,379,353.

Specification of Letters Patent. Patented May 24, 1921.

Application filed February 12, 1921. Serial No. 444,561.

To all whom it may concern:

Be it known that I, ECTOR F. MARCEAU, a citizen of the United States, residing at East Hartford, in the county of Hartford 5 and State of Connecticut, have invented a new and useful Improvement in Ink-Distributors for Printing-Presses, of which the following is a specification.

This invention relates to those appliances 10 which are adapted to be applied to printing presses for keeping the roll in the ink fountain supplied with the desired quantity of ink.

The object of the invention is to provide 15 a simple and cheap appliance which can be readily attached to common forms of printing presses and which has means that will automatically travel back and forth and uniformly distribute thick ink in the required 20 quantity to the desired area on the roll in the ink fountain when the press is running.

In the accompanying drawings Figure 1 shows a plan of an ink distributing appliance which embodies the invention. Fig. 2 25 shows a transverse section on the plane indicated by the dotted line 2—2 on Fig. 1. Fig. 3 on larger scale shows a plan of one end of the appliance with parts cut in section on the plane indicated by the dotted line 3—3 on Fig. 2.

The appliance illustrated comprises a pair 30 of brackets 1 which are designed to be fastened to the upper edges of the end walls 2 of the ink fountain 3 which is of common shape. The brackets support a rotatory shaft 4 provided with two reversely cut spiral grooves 5 between the brackets and a driving pulley 6 at one end. Two rods 7 connect and tie the brackets together and 35 movable on and guided by these rods is a yoke 8. A crescent-shaped block 9 is arranged to project into the shaft grooves. This block has a stem 10 which loosely fits a hole in the middle of the yoke. Projecting 40 from the stem of the block is a curved finger 11. Adjustably secured to the yoke and projecting into the fountain adjacent to the surface of the ink roll 12 is a distributing arm 13. On one of the rods 7, and adjust- 45 able along it, are two collars 14, which have

stop pins 15 that project parallel with the axis of the shaft into the path of the finger 11 on the crescent carried by the yoke. The collars are fastened in position, after being adjusted, by set screws 16. The ink roll 55 shaft 17 is supported by the end walls of the fountain and has a gear 18 that is designed to be engaged with the usual gearing of the press.

When the press to which the appliance is 60 attached is run the rotation of the grooved shaft feeds the crescent-block and this causes the yoke to travel along the rods and carry the distributing arm in the ink fountain along the face of the roll. When during the 65 travel of the crescent the finger engages a stop pin, the crescent is turned so as to be engaged by the walls of the reverse groove in the shaft, and consequently is then fed in the opposite direction. This carries the 70 yoke and distributing arm back until the finger engages the other stop pin and the crescent is again turned. By this means the distributing arm is caused to continue to travel back and forth and keeps the ink up 75 against the surface of the roll. The collars with the stop pins may be secured to the rod in any required positions so that the ink will be applied to the roll at only the desired section, and the distributing arm is set so 80 that the proper quantity of ink will be spread along the section of the roll to be inked.

The invention claimed is:

An ink distributor, comprising brackets, 85 rods connecting the brackets, a shaft provided with reverse spiral grooves supported by the brackets, means for rotating the shaft, a yoke movably supported by the rods, a distributing arm projecting from the 90 yoke, a block swiveled to the yoke, and extending into the grooves in the shaft, a finger extending from said block, collars adjustably secured to one of said rods, and stop pins projecting from the collars and adapted 95 to engage said finger and turn the block for reversing the travel of the yoke and distributing arm.

ECTOR F. MARCEAU.
